M. EVANIUK

CUTTING MACHINE

Filed April 14, 1923

Michael Evanuk Inventor

834 John H. Mackay
Attorney

UNITED STATES PATENT OFFICE.

MICHAEL EVANIUK, OF TOTENVILLE, NEW YORK.

CUTTING MACHINE.

Application filed April 14, 1923. Serial No. 632,059.

To all whom it may concern:

Be it known that I, MICHAEL EVANIUK, a citizen of Poland, residing at Tottenville, Staten Island, in the county of Richmond 5 and State of New York, have invented certain new and useful Improvements in Cutting Machines, of which the following is a specification.

This invention relates to a cutting and 10 slicing device which may be used for slicing, cutting, or comminuting generally, food products of various sorts, the invention having for an object to provide a novel and efficient device of this sort, a further object 15 relating to the provision of radial adjustment means for the cutting blades.

For further comprehension of the invention, and of the objects and advantages 20 thereof, reference will be had to the following description and accompanying drawings, and to the appended claims in which the various novel features of the invention are more particularly set forth.

Fig. 1 of the drawings is a side elevational 25 view of my improved device.

Fig. 2 is a transverse sectional view taken on the line 2—2 of Fig. 1.

Fig. 3 is a fragmentary axial sectional 30 view showing the means for radially adjusting the cutting blades.

Fig. 4 is an end view of the device.

Fig. 5 is a detail perspective view showing the blades applied to a hand slicer or 35 chopper.

As here embodied my improved device 40 comprises a frame consisting of the top horizontal bar 10 and the legs 10'. In these legs is journaled a shaft 13 which supports a number of rotary cutting elements. These 45 cutting elements each consists of a hub 15 from which project radially a number of guide arms 16 in which are slidably guided the knives 17, the hubs 15 being fixed on the shaft 13. Fixed in the inner ends of 50 the knives 17 are the pins 18 which may be screwed therein to permit of removal when desired, these pins projecting into spiral slots 19 in flanges 20 formed on the ends of sleeves 21 slidably freely surrounding the shaft 13. Formed in the sleeves 21 are the helically inclined slots 23 in which engage the ends of pins 24 fixed in a rod 55 25 slidable in the shaft 13, the latter being made hollow, these pins 24 passing through

longitudinal slots such as 26 in the wall of 60 said shaft.

For adjusting the rod 25 longitudinally in the shaft 13, a screw 30 is threaded into one leg 10' of the frame and has a swivel engagement as indicated at 31 with the rod 65 whereby the rod can rotate independently of the screw but is caused to move longitudinally with the latter. The screw has a head 32 thereon for turning purposes.

The frame 10 is supported on rollers or 70 wheels 35 which are journaled in the lower ends of the legs 10' and have fixed coaxially thereto the pulleys 36 over which are looped belts 37 looped also over pulleys 38 on the shaft 13 whereby, when the device 75 is caused to roll along a board or other surfaced object on which the material to be sliced is placed, the cutters will be caused to rotate. Handles such as 39 may be fixed on the frame for convenience in rolling the 80 device along.

It is believed that the manner of operation and use of my improved device will be readily understood from the above description, it being apparent that when the 85 device is moved along, the cutters will rotate; while the blades 17 can be given such radial adjustment as may be desirable, according to the material that is being sliced by turning screw 30 and so moving rod 25 90 longitudinally and imparting a rotary movement to the sleeve 21.

As indicated in Fig. 5 I may make use 95 of the blades 17 in a hand operated chopper when desired, the blades being removed from the guides 16 and fixed to the cross bars 45, it being understood that the blades will be formed with suitable tapped holes to receive the fastening screws 46. A handle 47 is also fixed to the blades.

Having thus described my invention what I claim as new and desire to protect by Letters Patent of the United States is as follows:

1. A device of the class described comprising a frame, a shaft journaled in said frame, a number of rotary cutters mounted on said shaft and each including radially adjustable knives, and a common adjusting means for all of said knives.

2. A device of the class described comprising a frame, a shaft journaled in said frame, a number of rotary cutters mounted

on said shaft and each including radially adjustable knives, and a common adjusting means for all of said knives, said means including a rod extending through an axial boring in said shaft.

3. A device of the class described comprising a frame, a shaft journaled in said frame, a number of rotary cutters mounted on said shaft and each including radially adjustable knives, and a common adjusting means for all of said knives, said means including a rod extending through an axial boring in said shaft, a number of pins on said rod, sleeves freely surrounding said shaft, said pins extending outward through longitudinal and inclined slots in the shaft and sleeves respectively, flanges on said sleeves having spiral slots formed therein, and pins on said knives engaging in said slots.

4. A device of the class described comprising a frame, a shaft journaled in said frame, a number of rotary cutters mounted on said shaft and each including radially adjustable knives, and a common adjusting means for all of said knives, said means including a rod extending through an axial boring in said shaft, a number of pins on said rod, sleeves freely surrounding said shaft, said pins extending outward through longitudinal and inclined slots in the shaft and sleeves respectively, flanges on said sleeves having spiral slots formed therein, and pins on said knives engaging in said slots, and a screw threaded into the frame and having swivel engagement with the end of the rod for adjusting the latter.
